[57] CLAIM

The ornamental design for a combined lavatory and pipe shroud, as shown and described.

DESCRIPTION

FIG. 1 is a top perspective view of a combined lavatory and pipe shroud showing our new design;

FIG. 2 is a front elevational view thereof;

FIG. 3 is a top plan view thereof;

FIG. 4 is a right side elevational view thereof the left side being a mirror image of the right side shown;

FIG. 5 is a cross sectional view taken on line 5—5 of FIG. 3;

FIG. 6 is a cross sectional view of the lavatory portion thereof, taken on line 6—6 of FIG. 3;

FIG. 7 is a cross sectional view of the shroud portion thereof, taken on line 7—7 of FIG. 2;

FIG. 8 is a bottom plan view thereof; and

FIG. 9 is a rear elevational view thereof.

The fragmentary broken line representations of holes in FIGS. 1, 3 and 6 are for purposes of illustration only.
